OPHTHALMIC WIRE MATERIAL

Raymond F. E. Stegeman, Greece, N. Y., assignor
to Bausch & Lomb Optical Company, Rochester, N. Y., a corporation of New York

Application November 16, 1949, Serial No. 6,071

Term of patent 14 years

(Cl. D57—1)

To all whom it may concern:

Be it known that I, Raymond F. E. Stegeman, a citizen of the United States, and a resident of the town of Greece, county of Monroe, and State of New York, have invented a new, original, and ornamental Design for Ophthalmic Wire Material, of which the following is a specification, reference being had to the accompanying drawing, forming a part hereof.

Fig. 1 is a top plan view of one side of a piece of ophthalmic wire material, showing my new design.

Fig. 2 is a top plan view of the other side of same.

Fig. 3 is a cross sectional view thereof taken on line 3—3 of Fig. 1.

I claim:

The ornamental design for ophthalmic wire material, substantially as shown.

RAYMOND F. E. STEGEMAN.
